UNITED STATES PATENT OFFICE.

CHARLES J. KINDEL, OF CHICAGO, ILLINOIS.

FOLDING BED.

1,118,556.

Specification of Letters Patent. Patented Nov. 24, 1914.

Application filed February 26, 1913. Serial No. 750,932.

To all whom it may concern:

Be it known that I, CHARLES J. KINDEL, a citizen of the United States, residing at Chicago, in the county of Cook and State of Illinois, have invented new and useful Improvements in Folding Beds, of which the following is a full, clear, concise, and exact description, reference being had to the accompanying drawing, forming a part of this specification.

My invention relates to improvements in folding beds and has for its object the production of a device in which the parts may be locked together under tension in closed position and unlocked and partly opened automatically from the front or rear.

A further object is the production of improved locking and unlocking means.

A further object is the production of improved means for holding the parts under tension either in locked or unlocked position.

A further object is the production of improved means for supporting the foot section.

A further object is the production of a device of simple yet efficient character, one that can be cheaply manufactured and not liable to get out of order.

These and such other objects as may hereinafter appear are attained by my device, an embodiment of which is shown in the accompanying drawing in which—

Figure 1 shows my device partly in elevation and partly in section with the parts unfolded and in the position to be used as a bed; Fig. 2 is a detail view of the locking mechanism; Fig. 3 represents a view on the line 3—3 of Fig. 2 looking in the direction indicated by the arrows; Fig. 4 represents top plan view of Fig. 1 partly in section.

Fig. 5 represents a view partly in elevation and partly in section showing my device in folded position. Fig. 6 represents a detail view in elevation showing a supporting leg. Fig. 7 represents a detail sectional view on the line 7—7 of Fig. 5 looking in the direction indicated by the arrows; Fig. 8 represents a sectional view on the line 8—8 of Fig. 5 looking in the direction indicated by the arrows; Fig. 9 represents a view on the line 9—9 of Fig. 5 looking in the direction indicated by the arrows.

Like numerals indicate like parts in the several figures of the drawings.

10 represents a side of the frame having

uprights 11 arranged at the rear thereof and arranged between the sides 10 and uprights 11 is a frame constructed preferably of metal having the sides 12 and front and rear connecting bars 13—14. These bars are preferably of angle iron construction. Secured to the uprights 11 are brackets 15 having slotted seats 16 that receive headed pins or lugs 17 on the cross-bar 14. A pivoted latch 18 is connected with the bar 14 and is of such a length that when the pin 17 rests in the seat 16 of the bracket 15 the extremity of the latch 18 will engage the face of the upright 11, so that by forcing the latch 70 downwardly from the position shown in Fig. 7 the extremity of the latch will bite into the face of the upright 11 forming a wedge securing the parts firmly together.

Brace-bars 19 extend across the frame 75 formed by the bars 12, 13, 14 and diagonally thereof to reinforce the frame and supported by the frame thus formed are uprights 20 positioned, adjacent the front of the casing and adjacent opposite sides thereof. The 80 seat or mattress supporting structure is formed of a series of sections 21, 22, 23, 24. The sections 22 and the sections 23 are arranged end to end and the adjacent ends are pivotally connected as at 25 to the uprights 20. The section 21 is pivotally connected by one end as at 26 with the free end of the section 22 and the sections 21 and 22 always remain within the casing. The section 23 is adapted to be folded in and out 90 of the casing and when unfolded projects beyond the front of the casing while the section 24 is pivotally connected adjacent one end with the free extremity of the section 23. A cross-bar 28 connects the free ends 95 of the section 24 while the cross bar 29 connects the free end of the section 21. Any number of cross bars may be provided in the frame thus formed and the elastic fabric 30 forming the support for the mattress is 100 secured to and foldable with this frame. A bracket 31 is connected with the section 22, see Fig. 1, and a guide link 32 is pivotally connected by one extremity with the bracket 31 and by its other extremity with the bar 12 and forms a support for the free end of the section 21.

When the frame is folded, the section 24 turns about the pivot 27 and the section 23 turns about the pivot 25 while the section 110 21 is lowered turning about the pivot 26, the section 22 will turn about the pivot 25 and

will drop into the casing, the sections 23 and 24 folding into the casing as shown in Fig. 5. The seat 33 is connected by links 34 with the section 23 to be suspended therefrom when the parts are unfolded, see Fig. 1, and stop pins 35 are provided on the seat frame and with which the links 34 engage, thus limiting the backward movement of the seat.

The pillow rests 36 are pivoted at one end as at 37 to the section 24 of the folding frame while the other end of the pillow rests are pivoted as at 38 to a bracket 39 secured to the upright 20. An elastic member 40 is connected to an upright 41 secured to the bar 12 and also to a link 42 which is pivoted as at 43 to the pillow rest and a stop pin 44 is provided for the link to rest against. When the sections are unfolded as in Fig. 1 the spring 40 is under tension and assists in folding the sections and when the sections are folded into the position shown in Fig. 5 the spring 40 is also under tension so that when the seat is unlocked the tension of the spring operates to raise the inner end 25 of the seat sufficiently to permit the operator to grasp and unfold the sections.

The legs 45 are pivoted to the end of the seat 33 and are adapted to engage a bracket or stop 47 while a spring 48 is provided which tends to move the leg into the position shown in Fig. 6 and to cause it to assume a position to support the seat when the sections are open. During the folding movement of the sections chains 49 which are secured to the cross bar 28 and also to the legs operate to pull the legs in the folded position and when the sections are folded the cross bar 29 assumes a position to rest upon the cross braces 19 and thereby forms a support for the end of the seat which is adjacent the back.

The seat and sections are locked in their folded position by a catch 50 pivoted as at 51 to a bracket 52 secured to the back 53 and the catch has a lip 54 which engages over a projection 55 on the seat when the seat is folded. A spring 56 tends to move the catch in a position to engage the shoulder 55 and to cause the lip 54 to stand in the path of the folding movement of the projection 55 but will yield to let the projection pass and then spring into locking position. This catch 50 is tripped to unlock the seat either from the front or from behind the back. It is operated from the front by means of a rod 57 having a pedal 58 and a crank portion 59. The crank portion is located in line with the catch 50 and is connected with the catch by means of a chain 60 so that when the pedal 58 is moved by the foot in the direction of the arrow in Fig. 9 the chain 60 will pull the catch 50 against the tension of the spring 56 to move the lip 54 off of the catch of the projection 55 to unlock the seat, at which time the tension

of the spring 40 will slightly raise the end of the seat. The catch is also operated from behind the back by means of a rod 61 which is connected to one end of a lever 62, the latter being pivoted intermediate its ends as at 63, and a chain 64 is connected to the other end of the lever and to a spring 65 at the top and behind the back. By pressing on the spring 65 the lever 62 will be rocked and the bar 61 will move the catch 76 and release the seat.

It will thus be seen that I have produced a very efficient locking means for holding the members in closed position, in combination with spring means which assists both in the opening and the closing of the bed, this being operable from either the front or the rear. When the structure is in closed position as indicated in Fig. 5 and the operator is standing in front, it is simply necessary to kick the pedal 58 which releases the catch 50 and the spring 40 immediately forces the seat upward to enable the operator to insert his hand between the seat and the back and complete the opening operation.

One of the great disadvantages in devices of this character heretofore has been that while it is absolutely necessary to grasp the seat in order to lift it, it is also essential that the seat and back fit closely together, these two requirements conflicting one with the other it becomes a rather difficult matter to take care of these matters in a single structure. As an alternative, a piece of folded tape is often fastened to the end of the seat and it is permitted to project up between the seat and the back in such a position that it may be grasped by the operator and used in opening the bed. This is all done away with by my device, which insures both a ready opening and tight closure between the seat and the back. If the operator happens to be behind the structure at the time he desires to open it, it is simply necessary to put his hand on the top of the member 11 reaching the fingers back under and around the spring member 65 when a slight pressure of the fingers will release the spring and cause the seat to fly upward.

In the improved leg or support for the foot of the bed section, I have provided a very efficient mechanism that will drop into place for supporting the bed when the tension on the chain 49 is removed, thus making it always ready for use, and will at the same time, when closed, be pulled into horizontal position parallel with the seat 33 and held in that position when the bed is in closed position as shown in Fig. 5.

Another important feature in this construction is the supporting plate 31 by means of which the head support 32 may be connected with the member 21 at a con-

siderable distance above the plane of the member, thus making it possible, when the parts are folded into closed position as shown in Fig. 5 to permit the member 21 to fall nearly horizontally and occupy a position close to the bottom of the structure, while the supporting member 32 remains at an angle to the member 21, thus making it easy to lift the parts without undue strain, and at the same time leave a large open space under the seat for the storage of the mattress and clothes. The construction illustrated in Fig. 1 showing the extension member 24 is also a valuable feature in that it permits the forming of a full width bed without in any way disturbing the back.

Heretofore in the opening of full width beds it has been necessary to turn up the back to get it out of the way in order to bring out the parts into unfolded position. In this construction, however, by having the shorter supplemental member 24 pivoted on the section 23 at 27 and to the pillow rest at 37 it is seen that a structure is provided that will automatically be forced downwardly as shown in Fig. 5 when the bed is folded, thus bringing it entirely out of the way, concealing it within the frame and still leaving sufficient mattress and clothes space underneath the seat. When the seat is kicked up it arises to an angle of something in the neighborhood of 30 to 45° from the horizontal before the position of the member 24 is materially changed. Then as the bed is further opened, the movement of the member 24 on the two pivots 27, 37, swings it about clear of the bottom of the back; so also in closing the bed, the reverse operation swings the member 24 about so that it clears the bottom of the back section which is rigidly secured in place.

Of course, it is clearly evident that many of the details of construction shown in embodiments of my device illustrated may be changed or others substituted therefor, without departing from the spirit of my invention.

I claim:

1. In a folding bed the combination with a main frame, a back section, a plurality of bed sections, a head rest mounted on one of said sections, means whereby said bed sections are held under tension when folded in the frame or in open position, said means comprising a spring fixed at one end within the frame and connected at the other end to said head rest.

2. In a folding bed the combination with a main frame, a back section, a plurality of bed sections, a head rest mounted on one of said sections, means whereby said bed sections are held under tension when folded in the frame or in open position, said means comprising a spring fixed at its lower end within the frame, a swinging link mounted

on said head rest and connected to the upper end of said spring.

3. In a folding bed the combination with a main frame, a back section, a plurality of bed sections, a head rest mounted on one of said sections, means whereby said bed sections are held under tension when folded in the frame or in open position, said means comprising a spring fixed at its lower end within the frame, a swinging link mounted on said head rest and connected to the upper end of said spring and automatic locking means for holding said bed section in closed position within the frame.

4. In a folding bed the combination with a main frame, a back section, a plurality of bed sections and means for holding said bed sections under tension, automatic means for holding said bed sections locked within the frame, and means for unlocking said locking means, said means being positioned at the bottom and front of said folding bed.

5. In a folding bed the combination with a main frame, a back section, a plurality of bed sections and means for holding said bed sections under tension, automatic means for holding said bed sections locked within the frame, and means for unlocking said locking means, said means being positioned at the bottom and front of said folding bed and also at the back of said folding bed.

6. In a folding bed the combination with a main frame, a back section, a plurality of bed sections, a head rest mounted on one of said sections, means whereby said bed sections are held under tension when folded and locked in the frame, said means comprising a spring fixed at its lower end within the frame, a swinging link mounted on said head rest and connected to the upper end of said spring, and means positioned at the bottom and front and also at the back of said folding bed for unlocking said locking means.

7. In a folding bed the combination with a main frame, a back section, a plurality of bed sections and means for holding said bed sections under tension, automatic means for holding said bed sections locked within the frame, and means for unlocking said locking means, said means being positioned at the bottom and front of said folding bed, and comprising a connecting rod extending through the bottom of the structure, having a pedal in front and a crank arm at its inner end and connecting with said locking means.

8. In a folding bed the combination with a main frame, a back section, a plurality of bed sections, a head rest mounted on one of said sections, means whereby said bed sections are held under tension when folded in the frame and in open position, said means comprising a spring fixed at one end within the frame, a swinging link mounted on said head rest and connected to the upper end

of said spring, a front support for said bed sections when open and means whereby the front end section may be lowered to the bottom of and within said main frame.

5. 9. In a folding bed the combination with a main frame, a back section, a plurality of bed sections, a head rest mounted on one of said sections, means whereby said bed sections are held under tension when folded in 10 the frame and in open position, said means comprising a spring fixed at its lower end within the frame, a swinging link mounted on said head rest and connected to the upper end of said spring, a front support for 15 said bed sections when open, and means whereby the front end section adjacent the spring may be lowered to the bottom of and within said main frame, said means comprising a supporting plate mounted on said 20 section, a support pivoted at its upper end to said plate and at its lower end to the frame.

10. In a folding bed the combination with

a main frame, a back section, a plurality of bed sections, means for holding said bed sections under tension and locked within the frame and means for unlocking said locking means, said unlocking means being mounted on the underside of the back of 25 said structure below the top rail.

11. The combination with a frame, of a plurality of foldable bed sections hingedly connected within said frame, a releasable latch for retaining said bed sections in 30 closed relation with respect to said frame and tension means for causing said bed sections to spring upward into a position readily accessible for unfolding when said latch is released.

I witness whereof, I have hereunto subscribed my name in the presence of two witnesses.

CHARLES J. KINDEL.
